[57] **ABSTRACT**

New alkyl sulfonic acid esters of 1,3,2-oxazaphosphacyclic compounds of formula I

These new compounds produce a high immunosuppressing activity in humans.

4 Claims, No Drawings

ALKYLSULFONIC ACID ESTERS OF
1,3,2-OXAZAPHOSPHACYCLIC COMPOUNDS
RELATED APPLICATION

This application is a division of our copending application Ser. No. 225,273, filed Feb. 10, 1972, now U.S. Pat. No. 3,828,090, granted Aug. 6, 1974.

The present invention is related to alkyl sulfonic acid esters of 1,3,2-oxazaphosphacyclic compounds which produce a high immunosuppressing activity. The invention is further related to process for the production thereof and to pharmaceutical preparations containing the same.

The new compounds according to the present invention correspond to the formula I

wherein R is a halogen atom, preferably a chlorine atom, R₁ is hydrogen and R₂ is a lower alkyl group with 1 to 4 carbon atoms which is substituted with a lower alkyl sulfonic ester group having a straight or branched lower alkyl chain with 1 to 6 carbon atoms, and alk represents a straight or branched alkylene group with 2 or 3 carbon atoms in the chain and, if branched, with a total of 3 or 4 carbon atoms, X represents oxygen, Z represents a hydrogen atom and m is 3.

Because of their favourable compatibility their high immunosuppressing activity those compounds of formula I are preferred, wherein alk is the group —CH₂CH₂—. Among this group of compounds those compounds show a particularly high immunosuppressing activity and therefore are most preferred wherein the lower sulfonic acid ester group is the methylsulfonic acid ester group. It is surprising that the compounds of formula I show a strong immunosuppression which activity has not been known up to now with alkyl sulfonic acid esters. The immunactivity in connection with the Brucella immunisation of rats is used to demonstrate this activity.

The new compounds of formula I are produced by using methods known as such. The process for the production of the compounds according to the present invention comprises

A. subjecting a compound of formula IV

wherein R₃ has the same meaning as R in formula I or is a hydroxy group, R₄ has the same meaning as R₁ in formula I alk and X have the same meaning as in formula I and X₁ is a halogen atom, preferably a chlorine atom, to reaction with a compound of formula V

wherein R₅ has the same meaning as R₄ in formula IV and Z and m have the same meaning as in formula I, or B. subjecting a compound of the general formula VI

VI

10 wherein R₃ and R₄ have the same meaning as in formula IV and alk has the same meaning as in formula I, to reaction with a compound of formula VII

VII

15

1 I 20 wherein X₁ has the same meaning as in formula IV, R₅ has the same meaning as in formula V and X, Z and m have the same meaning as in formula I, or C. subjecting a compound of formula VIII

VIII

25 wherein R₅ has the same meaning as in formula V and X, Z, alk and m have the same meaning as in formula I, to reaction with a compound of formula IX

30 H⁺ R₄ O IX

wherein R₃ has the same meaning as in formula IV, and converting the hydroxy group in the resulting compounds of formula X

X

40

45 wherein R₅ carried a hydroxy group, into the group —OSO₂R₆, R₆ being a straight or branched lower alkyl group having from 1 to 6 carbon atoms, by subjecting said hydroxy compound to reaction with a sulfonic acid halogenide R₆SO₂Hal, R₆ having the same meaning as above and Hal being a halogen atom, preferably a chlorine atom.

50 The reactions are preferably carried out in the presence of an inert solvent such as acetonitrile or a lower halogenate hydrocarbon such as chloroform or methylene chloride, or in an ether such as diethylether or dioxane, or in an aromatic hydrocarbon such as benzene or toluene. The reaction is carried out at an elevated temperature ranging from room temperature to the boiling point of the reaction mixture.

55 The reactions are preferably carried out in the presence of an acid binding agent. The acid binding agent should be present in an amount ranging from 1 to 2 mole equivalents. There are numerous known alkaline compounds which may be used as acid binding agents such as alkali metal and alkaline earth metal carbon-

60

ates and bicarbonates and particularly tertiary amines such as triethylamine and pyridine.

Usual carrier products for pharmaceutical preparations, which may contain a compound according to formula I as active agent are pharmacologically inert products as they are known for the production of tablets, dragees, suppositories and injection solutions.

The following examples further illustrate the present invention without however limiting the same thereto. The compounds according to the present invention are characterized by their infrared spectra and show characteristic

P=O— bands at 1188 to 1275 cm⁻¹,
—C—SO₃—C— bands at 1330 to 1376, 1165 to 15 1175, 905 to 975 and 787 to 805 cm⁻¹,
—P—O—C— bands at about 1050 and 975 cm⁻¹ and NH— bands at 3200 to 3300 cm⁻¹.

EXAMPLE 1

2-(2-Chloroethylamino)-3-(3-methylsulfonyoxypropyl)- tetrahydro-2H-1,3,2-oxazaphosphorine-2-oxide

A solution of 39.2 g. of 2-chloroethyl-phosphoric acid amide dichloride in 160 cc. of anhydrous dioxane is added to a solution of 26.7 g. of dipropanolamine and 42 g. of triethylamine in 120 cc. of anhydrous dioxane dropwise at room temperature within an hour. Stirring is continued for further 2 hours and the precipitated triethylamine hydrochloride is filtered off with suction. The filtrate is evaporated in a water jet vacuum and the residue is dissolved in chloroform. The solution is neutralized with ethereal hydrochloric acid, the solution thereafter is dried and the solvent is again evaporated. 2-(2-chloroethylamino)-3-(3-hydroxypropyl)-
tetrahydro-2H-1,3,2-oxazaphosphorine-2-oxide is obtained as a yellow-brown oil.

Yield: 14.4 g. (28% of the theoretical)

A solution of 14.4. g of the above compound and 5.7 g. of triethylamine in 110 cc. of anhydrous dioxane is added to a solution of 6.45 g. of methanesulfonylchloride in 65 cc. of anhydrous dioxane dropwise with stirring at a temperature of 30° C. within 30 minutes. The separated triethylamine hydrochloride is filtered off and the filtrate is evaporated in a vacuum. The residue is dissolved in a mixture of 1 part of isopropanol and 1 part of ether. The solution is allowed to stand for 2 hours in an ice-bath with scratching at intervals. The separated crystals are filtered off with suction and are washed in a mixture of isopropanol and ether and thereafter with ether alone. The product is purified by extraction with ether in a soxhlet apparatus.

Yield: 6.5 g (34.6% of the theoretical)

F.: 72° C.

EXAMPLE 2

2-(2-Chloroethylamino)-3-(2-methylsulfonyoxyethyl)- tetrahydro-2H-1,3,2-oxazaphosphorine-2-oxide

A solution of 26.5 cc. of HCl in ether (159.7 mg./cc.) is added to a solution of 32.9 g. of 2-ethyleneimino-3-(2-methoxyethyl)-tetrahydro-2H-1,3,2-oxazaphosphorine-2-oxide in 175 cc. of anhydrous methylene chloride dropwise with vivid stirring within 20 minutes at 30° C. Thereafter, the methylene chloride phase is decanted off from the highly viscous precipitate. The methylene chloride solution is filtered over activated charcoal and evaporated in a vacuum. The resulting oil is dissolved in methylene chloride and ether is added in

such an amount to yield a methylene chloride : ether proportion of 1:1. The precipitated oil is again dissolved in methylene chloride and ether is added as previously and these steps are repeated until the precipitated oil is no more soluble in methylene chloride. The combined methylene chloride/ether extracts are filtered over activated charcoal and evaporated in a vacuum. The resulting oily product is dissolved in methylene chloride and the solution is washed three times with chilled water and dried. The solvent is evaporated, thus yielding into a yellow viscous oil.

Yield: 20.8 g.

n_D²²: 1.4967.

EXAMPLE 3

The following recipe is used for the production of 100,000 dragees containing each 50 mg. of the active compound according to the present invention:

Compound according to Example 1	5.000 kg.
Corn starch	4.000 kg.
Polyvinylpyrrolidone	0.060 kg.
Talcum	0.575 kg.
Magnesium stearate	0.250 kg.
	14.000 kg.

25

30

45

50

55

60

65

The crystalline active compound is passed together with 3 kg. of corn starch through a sieve having a mesh size of 1 mm. The products are thoroughly mixed and a paste is formed with a 10% solution of the polyvinylpyrrolidone in isopropanol. The moist product is granulated by passing it through a sieve having a mesh size of 3 mm. It is then dried and ground to a particle size of 1 mm. Finally, the remaining auxiliary products of the above recipe are sieved and thoroughly admixed and 100,000 dragees are pressed each weighing 140 mg., having a diameter of 7 mm. and a camber diameter of 6 mm. The resulting kernels are coated in manner known per se by first applying a layer resistant to the gastric juices giving each kernel a weight of 170 mg., then applying a cover until a kernel weight of 205 mg., smoothing the surfaces of the kernels until a kernel weight of 215 mg. and thereafter applying colorlayers up to a kernel weight of 240 mg. Finally, the coated kernels are rendered glossy by applying a layer of hard wax.

EXAMPLE 4

A dry mix of active compound and sodium chloride is filled into glass to be for the production of injection solution. In the last step of purification by recrystallization of the active compound according to Example 1, the solution thereof is passed through a filter holding back germs. The further processing is effected under aseptic conditions. The crystallized compound is separated by centrifugation and dried and held in an atmosphere of ethylene oxide. A sample is taken and checked for purity and sterility. After clearance of further processing is obtained, the compound is mixed with sterilized sodium chloride p.a. in a weight proportion of 100 to 45 under aseptic conditions, thus producing a finely divided homogenous mix. Another sample is taken and tested for its content in active compound, for sterility and freedom of pyrogenous compounds. After clearance of further processing, 145 mg. of the mix are filled into flasks of 10 ml. each under aseptic conditions and in an atmosphere of nitrogen. The flasks are closed with aseptic stoppers of butyl caoutchouc. The final

check is made in accordance with the recommendations of the Section "Testing for good quality and sterility" of the German Federal Health Administration. In order to produce injection solutions, 5 cc. of water purified for injection solutions are added to the content of a flask which is dissolved therein. The compounds according to the present invention are useful in the treatment of autoimmune diseases (autoaggressive diseases) in humans, such as chronic rheumatoid arthritis, psoriatic arthropathy, autoimmun-haemolytic anemia, cold agglutination disease, lupus erythematoses, Sjögren's disease, skleroderma, severe myasthenia, polyarteritis nodosa and nephrotic syndrome. The compounds are preferably applied in a daily dose ranging from 2 to 4 mg./kg.. A particularly useful and therefore most preferred compound is that of example 1.

What we claim is:

1. Alkyl sulfonic acid esters of 1,3,2-oxazaphosphacyclic compounds of formula I

10

5

wherein R represents a halogen atom, R₁ is hydrogen, and R₂ is a lower alkyl group having from 1 to 4 carbon atoms which is substituted with a lower alkyl sulfonic acid ester group having a straight or branched lower alkyl group with 1 to 6 carbon atoms, and alk represents a straight or branched alkylene group having 2 or 3 carbon atoms in the chain and, if branched, having a total number of 3 or 4 carbon atoms, X represents oxygen, Z represents hydrogen, and m is 3.

2. A compound according to claim 1 wherein alk is —CH₂CH₂—.

3. A compound according to claim 2 wherein R is chlorine.

4. 2-(2-chloroethylamino)-3-(2-methylsulfonyoxyethyl)-tetrahydro-2H-1,3,2-oxazaphosphorine-2-oxide.
